UNITED STATES PATENT OFFICE.

CHARLES I. MANDEL, OF NEW YORK, N. Y.

BOY'S SUSPENDERS.

SPECIFICATION forming part of Letters Patent No. 741,405, dated October 13, 1903.

Application filed January 10, 1903. Serial No. 138,515. (No model.)

To all whom it may concern:

Be it known that I, CHARLES I. MANDEL, a citizen of the United States, residing in New York, borough of Brooklyn, and State of New York, have invented certain new and useful Improvements in Boys' Suspenders, of which the following is a specification.

This invention relates to certain improvements in boys' suspenders—that is to say, suspenders that are buttoned to the waistbands of boys' trousers and drawers for supporting the same in place of the waists or blouses heretofore used for this purpose.

The waistbands of boys' trousers in general use are provided with nine approximately equidistant buttonholes, which are applied to the buttons attached to the lower end of the waist or blouse. All these buttons have to be buttoned on and unbuttoned when dressing or undressing. This time-consuming buttoning or unbuttoning of the trousers and drawers can be obviated by the use of a pair of suspenders which after being buttoned on the trousers remain in position thereon; and for this purpose my invention consists of a pair of suspenders for boys' trousers which comprise adjustable shoulder-straps, suspender-ends attached by links to the rear and front ends of the shoulder-straps, V-shaped straps connecting the ends of the shoulder-straps at the front sides and rear, said V-shaped straps being looped through the links at the ends of the shoulder-straps, so as to be adjustable, and provided with tabs having two buttons each for attachment to the trousers and drawers, one end of the V-shaped front strap being provided with a fastening device, so as to be detachable from the front end of the shoulder-strap, as will be fully described hereinafter and finally pointed out in the claims.

In the accompanying drawings, Figure 1 represents a perspective view of my improved boys' suspenders. Fig. 2 is also a perspective view showing a modified construction of the same. Figs. 3 and 4 are detail vertical transverse sections, respectively, on line 3 3, Fig. 1, and line 4 4, Fig. 2. Fig. 5 is a perspective view of the rear part of the improved suspenders, showing the doubled-up straps passing through the links; and Fig. 6 is a detail view of Fig. 5, showing a section of the

doubled-up straps, taken just when the straps emanate from the links of the shoulder-straps.

Similar letters of reference indicate corresponding parts.

Referring to the drawings, A represents the shoulder-straps of my improved suspenders for boys' trousers. Each shoulder-strap A is provided with the usual fastening-buckle a, so that the straps can be lengthened or shortened, as required. Each shoulder-strap is further provided at the front and rear ends with wire links a', to each of which a single suspender-end B, provided with one or two buttons b, is attached. The rear parts of the shoulder-straps A are connected by a transverse brace-piece D, so that the shoulder-straps are held at the proper distance from each other at the back. The links a' at the front ends and the links at the rear ends of the shoulder-straps A are connected by V-shaped straps C, which are doubled up and passed through the links a', the V-shaped straps being each connected at their lower ends or the apices with a link d, to which a short tab d', with two buttons d', is applied, so that four additional suspender-ends are obtained, to which the waistband of the trousers and waistband of the drawers can be attached, so that a reliable connection of the trousers and drawers with the suspender-ends and V-shaped connecting-straps is obtained. The V-shaped straps C are doubled up—that is, consist of two straps g and g'. Beginning with the right-hand side of Fig. 5, strap g' rests on link a', while strap g is uppermost and passes over strap g'. Both straps pass then to link d, and the strap g becomes nearest to link d, while strap g' passes over strap g, and at the next link a' strap g' again rests on a', while strap g is uppermost and passes over strap g'. As the V-shaped straps are doubled up and passed through the links at the ends of the shoulder-straps, as well as the lower connecting-straps, the shifting of the V-shaped straps can take place according to the size of the trousers, and the distance between the buttonholes is the same, so that the free adjustment of the suspenders to the trousers takes place. The straps g and g' are joined at their ends, and one of these ends is fastened to one of the links a', as shown in Figs. 1 and 2, while the other end is made de-

tachable by connecting it by means of a spring-fastener *f* to the under side of the front suspender-end *B*, which is supported by the same link *a'* to which the end of the V-shaped strap is fastened, as shown in Fig. 1. This connection of the V-shaped front strap is necessary, so as to permit the throwing off of the shoulder-straps from the shoulders when taking off the trousers and the replacing of the same when putting on the trousers. Any of the well-known fastening devices can be used for this purpose, but preferably the well-known socket-and-spring fastening device.

The straps *g* and *g'*, forming the V-shaped straps *C*, may be joined by sewing immediately between the links *a'* and links *d*, as shown in Fig. 5, or may be arranged simply as shown in Fig. 1.

Instead of arranging links *d* and tabs *d'* at the lower ends of the V-shaped connecting-straps *C*, as shown in Figs. 1 and 3, the V-shaped straps can be connected at their lower ends or apices by means of triangular webbings *e*, to which the buttons *e'* for the waistbands of the trousers and drawers are applied, as shown in Figs. 2 and 4, while the upper ends are doubled up, so as to pass from the links *a'* similarly to the manner shown in Figs. 1 and 5. The webbed connections *e* and the buttons on the same end at the apices of the V-shaped straps *C* correspond to the buttons of the tabs *d'* in Figs. 1 and 3 and are the equivalent of the same.

The suspender-straps may be made of elastic material and the suspender-ends and V-shaped straps of inelastic webbing, or the suspender-ends and V-shaped straps may be of elastic material and the suspender-straps of inelastic webbing, as desired.

The improved suspender for boys' trousers furnishes an evenly-divided support for the trousers and drawers, and thereby a very comfortable support for the same, in which the strain on the suspenders, whatever be the position of the body, is transmitted by the suspender-straps, while the shifting of the

V-shaped straps and the adaptability of the shoulder-straps permit the use of one and the same size of suspenders for trousers of different sizes and drawers.

Having thus described my invention, I claim as new and desire to secure by Letters Patent—

1. A pair of boys' suspenders, consisting of shoulder-straps provided with adjusting devices, links at the front and rear ends of the shoulder-straps, suspender-ends applied to said links, doubled-up V-shaped straps passing through the links, and tabs on the lower ends or apices of said V-shaped straps, substantially as set forth.

2. A pair of boys' suspenders, consisting of adjustable shoulder-straps provided with links at their front and rear ends, suspender-ends applied to said links and provided with buttons, doubled-up V-shaped straps passing through the links and connecting one with the other, links at the lower ends or apices of the V-shaped straps, and tabs supported by said links and provided with buttons respectively for the waistband of the trousers and drawers, substantially as set forth.

3. A pair of boys' suspenders, consisting of adjustable shoulder-straps, links at the front and rear ends of said straps, V-shaped straps connecting the links at the ends of the shoulder-straps at the front, sides and rear, suspender-ends applied to the front and rear ends of the shoulder-straps, tabs at the lower ends or apices of the V-shaped straps, and means for connecting one end of the V-shaped front strap with the suspender-end of one of the shoulder-straps to permit the opening of the V-shaped front strap, substantially as set forth.

In testimony that I claim the foregoing as my invention I have signed my name in presence of two subscribing witnesses.

CHARLES I. MANDEL.
